REFRIGERATING MACHINE

Harley H. Bixler, Schenectady, N. Y., assignor to
General Electric Company, a corporation of
New York

Application January 11, 1935, Serial No. 1,337

26 Claims. (Cl. 230—30)

My invention relates to refrigerating machines. Refrigerating machines of the compression type include a compressor for compressing a gaseous refrigerant, the compressor being driven by an electric motor or the like. The gaseous refrigerant so compressed is cooled and liquefied in a suitable condenser from which it flows to an evaporator or other cooling unit. The liquid refrigerant is caused to boil in the cooling unit by the absorption 5 of heat from surrounding objects. The gaseous refrigerant thus formed by the boiling in the cooling unit is returned to the compressor and the cycle is repeated. In operating machines of the type described, it is desirable to provide some 10 mechanism for unloading the compressor during the starting period in order that the motor may start under a comparatively light load and hence not draw an excessive starting current. It is also desirable that the unloading mechanism should 15 be arranged to unload the compressor when the supply of current to the motor has been shut off and the motor is coasting to a stop in order to minimize vibration of the machine.

In addition I have found it desirable to arrange 20 the unloading mechanism in such a manner that the compressor will be unloaded when the amount of lubricant supplied to the bearings of the machine is insufficient in order that damage, resulting from running the parts fully loaded when they 25 are not properly lubricated, may be avoided. This problem is of particular importance in the case of closed compression system refrigerating machines in which the compression system contains lubricant such as oil. In such machines the 30 lubricant is mingled with the refrigerant during at least a part of the operating cycle and if the lubricant is not thoroughly purged of gaseous refrigerant before it is supplied to the parts which it is intended to lubricate it may be so thinned by 35 the refrigerant that improper lubrication will be had.

It is an object of my invention to provide an improved unloading mechanism for refrigerant compressors or the like.

40 It is a further object of my invention to provide a compression type refrigerating machine or the like including apparatus for unloading the compressor thereof when an insufficient amount of lubricant is supplied to lubricate said machine.

45 Another object of my invention is to provide a compression type refrigerating machine or the like including apparatus for unloading the compressor thereof when the lubricant supplied thereto contains too large a percentage of refrigerant

therein to insure adequate lubrication of said machine.

Another object of my invention is to provide an improved refrigerating machine of the type described which will be efficient in operation and in which any noise caused by its operation is minimized.

Further objects and advantages of my invention will become apparent as the following description proceeds and the features of novelty 10 which characterize my invention will be pointed out with particularity in the claims annexed to and forming a part of this specification.

For a better understanding of my invention, reference may be had to the accompanying drawings, in which Fig. 1 is a side elevation, partly in section, of a refrigerating machine embodying my invention; Fig. 2 is a plan view of the casing and motor driven compressor included in the refrigerating machine shown in Fig. 1 the top of the compressor and part of the top of the motor being broken away; Fig. 3 is a plan view of the rotary lubricant pump on the line 3—3 of Fig. 5; Fig. 4 is a partial bottom plan view of the Scotch yoke mechanism of the compressor shown in Fig. 1; Fig. 5 is a side elevation partly in section along the line 5—5, of the apparatus shown in Fig. 2; Fig. 6 is a fragmentary sectional view of the valve and unloader mechanisms included in the refrigerating machine shown in Fig. 1; Fig. 7 is a detail 30 view of a valve assembly for the compressor included in the refrigerating machine shown in Fig. 1; Fig. 8 is a sectional view along the line 8—8 of the relief valve included in the valve assembly shown in Fig. 7, and Fig. 9 is a fragmentary enlarged longitudinal sectional view of the unloader cylinder.

Referring to the drawings, in Fig. 1 I have shown a refrigerating machine provided with an hermetically sealed casing 10 made up of an upper casing section 11 and a lower casing section 12, the adjacent edges of these sections being welded together over a reinforcing ring 13 as indicated at 14. The casing sections 11 and 12 are preferably made of steel, and mounted on a removable cabinet top 12a. A refrigerant compressor 15 and an electric driving motor 16 therefore are contained within the hermetically sealed casing 10. The compressor 15 is secured to the top of the driving motor 16 by bolts 17 and 18, 45 thus forming a compact unitary structure. This unitary structure is mounted in the casing 10 on three vertical helical springs 19, 20, and 21. The upper ends of springs 19, 20, and 21 are secured to feet 22, 23, and 24, respectively, these feet being 50 55

welded to the periphery of the frame of the motor 16 at equally spaced intervals of approximately 120°. The lower end of the spring 20 is supported on an indentation 25 formed in the lower section 12 of the casing 10, as shown in Fig. 5. The springs 19 and 21 are also supported on similar indentations formed in the lower section 12 of the casing 10. A bumper ring 26 surrounds the unitary structure and is secured in a slot 27 in a foot 23, as illustrated in Fig. 5. Similar slots are formed in the feet 22 and 24 for supporting the bumper ring 26. A series of stops 28, 29, and 30 are welded to the inner side wall of the casing 10 at spaced intervals of approximately 120° as best shown in Fig. 2. These stops limit the vertical movement of the unitary structure by engagement with the bumper ring 26.

The mounting arrangement for the unitary compressor and motor structure described above forms no part of my present invention, but is described and claimed in my application Serial No. 1,338, filed January 11, 1935, and assigned to the General Electric Company, the assignee of my present invention.

As shown in Fig. 5, the driving motor 16 is provided with a rotor 31 which is mounted on a hollow vertical shaft 32 within a stator 33, the stator 33 having energizing windings 34 mounted in slots therein in the usual manner. End shields 35 and 36 are provided for the upper and lower ends, respectively, of the stator 33, being secured thereto by bolts 37. The shaft 32 is supported in upper and lower bearings 38 and 39, respectively. The upper bearing 38 is of the self-aligning sleeve type, having a relatively large axial length as compared to its diameter and is loosely mounted in a cylindrical bore 40 formed in the upper end shield 35 and preferably having a sucking fit therewith. Rotation of the bearing 38 in bore 40 is prevented by a pin 38a. The lower bearing 39 is a machined surface of a cylindrical bore formed in the lower end shield 36 in axial alignment with the shaft 32. Since the compressor 15 is located closely adjacent the upper bearing 38, most of the lateral thrust on the shaft 32 is taken up by this upper bearing and the lower bearing 39 may consequently be relatively short as compared to its diameter and hence need not be of the self-aligning type. The lower end of the shaft 32 is supported on a retaining plate 41 which is secured to the lower end shield 36 by bolts 42, which are in threaded engagement with tapped holes 43 provided in the lower end shield 36. The upper surface of the retaining plate 41 is ground 55 to provide a smooth flat surface on which the end of the shaft 32 may freely rotate. Any downward axial thrust on the shaft 32 is thus taken up by the retaining plate 41. By the use of such a bearing arrangement contained within the end shields 35 and 36, a compact structure having a minimum vertical height is provided.

The upper end of the shaft 32 is provided with a crank arm 44 and a counterweight 45. The compressor 15 is of the Scotch yoke type and 65 includes a cylindrical slide 46, and during reciprocation of a piston 49 by the crank 44 the slide is reciprocated in a cross-head 47, the crank 44 passing through an elongated slot or opening 48 in the lower side of the cross-head 47. The piston 49 is welded to the cross-head 47 and is reciprocated in a bore 50 of a compression cylinder 51. The rotary movement of the crank 44 causes a reciprocatory movement of the slide 46 in the cross-head 47, and a reciprocatory movement of

the piston 49 in the bore 50 of the compressor cylinder 51.

The particular construction of the piston and yoke illustrated is not my invention, but is the invention of Christian Steenstrup, and is described and claimed in his application, Serial No. 12,390, filed March 22, 1935, and assigned to the General Electric Company, the assignee of my present invention.

One end of the bore 50 of the compression cylinder 51 is closed by a flat valve plate 52, which is secured to the cylinder 51 by bolts 53. The bolts 53 also hold a muffle box 54 in place on top of the valve plate 52. As best shown in Fig. 7, the valve plate 52 is provided with a relatively large intake opening 55, which is closed by a flexible inlet valve 55a. The inlet valve 55a is preferably made in the form of a tongue which is an integral part of a thin plate of steel or the like 55b having the same peripheral dimensions as the valve plate 52 and having an opening 55c. A series of relatively small exhaust ports 56 arranged in a circle are also provided in the valve plate 52 and are normally closed by a disk-shaped flexible exhaust valve 56a. The exhaust valve 56a is provided with a disk-shaped retainer 56b, the retainer 56b and exhaust valve 56a being secured to the valve plate 52 by a rivet 57 which passes through registering central apertures in the retainer and exhaust valve. The valve plate 52 is also provided with a relief port 58, which is closed by a relief valve 59. The relief valve 59 is normally biased to the closed position by a helical compression spring 60 which urges a stud 61 against the valve 59. The tension of the spring 60 is so proportioned that if the pressure in the cylinder bore 50 exceeds a predetermined safe value, because of the failure of the exhaust valve 56a to open or for some other reason, the valve 59 will open and bleed a portion of the compressed fluid in the cylinder bore 50 into the interior of the casing 10.

The general arrangement of the valve assembly described above forms no part of my present invention, but is described and claimed in my application Serial No. 26,067, filed June 11, 1935, and assigned to the General Electric Company, the assignee of my present invention.

A body of oil or other lubricant 62 is maintained in a reservoir formed in the lower section 12 of the casing 10. Lubricant is continuously recirculated from this reservoir in a closed series circuit including the contacting moving surfaces of the compressor 15 and motor 16 to lubricate the same and back to the reservoir, the entire lubricating system for the machine thus being contained within the hermetically sealed casing 10.

I provide an unloader mechanism for controlling the loading and unloading of the compressor 15 which is operated by lubricant circulating in this series lubricant circuit. When the motor 16 is in operation, lubricant is drawn upwardly through a conduit 63 by a rotary pump 64, which is driven by the shaft 32 of the motor 16. As best shown in Fig. 3, the rotary pump 64 includes a pair of oppositely extending blades 65 and 66, which are slidably mounted in slots 67 and 68, respectively, formed in the lower end of the shaft 32. The lower end of the shaft 32 and the blades 65 and 66 rotate in a chamber formed by a cylindrical bore 69 in a casing plate 70, the center of the bore 69 being eccentric with respect to the center of the shaft 32. The retaining plate 41 and a cover plate 71 are secured to the lower

side of the casing plate 70. The cover plate 71, the retaining plate 41 and the casing 70 are held in their assembled position by the bolts 42. As the blades 65 and 66 rotate in the chamber 69, in a clockwise direction, for example, as viewed in Fig. 3, lubricant is drawn into the chamber 69 through the conduit 63 and an intake opening 72 formed in the retaining plate 41 due to the increasing volume of the space behind the blade 65. Upon further rotation of the shaft 32, the lubricant is expelled under pressure from the chamber 69 through an outlet opening 73 formed in the retaining plate 41. This pumping action is due to the decreasing volume of the space in front of the blade 66 as the rotation of the shaft 32 continues. The blades 65 and 66 are pushed outwardly against the wall of the chamber 69 by centrifugal force and by the pressure of the lubricant in passage 75. Lubricant discharged through an outlet opening 73 in the retaining plate 41 passes into a depression 74 formed in the cover plate 71 and then upwardly through the central axially extending passage 75 formed in the shaft 32 of the motor 16. A portion of the lubricant passing upwardly through the passage 75, flows through a passage 76 which communicates with the lower portion of the passage 75, and passes through the passage 76 to a groove 77 formed in the lower bearing 39 of the shaft 32 thus lubricating the bearing 39. A horizontal passage 78 communicating with the upper portion of the passage 75 is also formed in the shaft 32 and communicates with a circular groove 79 formed in the upper bearing 38. Lubricant for the bearing 38 is supplied thereto from the passage 75 through the passage 78 and groove 79. The surfaces of the bearings 38 and 39 may be provided with cross grooves communicating with the grooves 77 and 79 in order to more thoroughly distribute the lubricant over the surface of the bearings. A further portion of the lubricant under pressure in the passage 75 passes upwardly therefrom through a passage 80 formed in the crank 44 to the top of the latter and lubricates the contacting surfaces of the crank 44 and the slide 46, as well as the contacting surface of the cross-head 47. A second passage 81 is also formed in the crank 44 in order to allow lubricant to pass downwardly from the top of the crank 44 to the contacting surfaces of the slide 46 and the crank 44 in order to insure thorough lubrication of the same. A passage 82 is provided in the upper end shield 35 of the motor 16 which communicates with the groove 79 formed in the upper bearing 38 and supplies lubricant under pressure therefrom to an unloader 83. The passage 82 communicates at its upper end with a bore 84 of an unloader cylinder 85 of the unloader 83. In the illustrative form of my invention, the compressor cylinder 51 and unloader cylinder 85 are made as an integral structure, the bores 50 and 84, respectively, of the cylinders being arranged in parallel relationship. The unloader 83 includes a cup-shaped piston 86 which is provided with a cylindrical sleeve 87, the piston and sleeve being brazed or otherwise secured together. The piston 86 and sleeve 87 constitute a movable wall of the cylinder 85. One end of a U-shaped operating rod 88 is provided with a disk 89 which is secured to the piston 86. A helical compression spring 90 which is held in place between the disk 89 and a retaining plate 91 secured to the muffle box 54 by the bolt 53 normally biases the operating rod 88 to a position in which it holds the inlet valve 55a in the open position thus unloading the

compressor 15. The piston 86 is provided with a depression 92 which engages a complementary notch 93 formed in the disk 89 thereby preventing rotation of the disk in the piston 86.

A part of the lubricant supplied under pressure to the bore 84 through the passage 82 passes therefrom through a sharp edged orifice 94 in the sleeve 87 to a passage 95. The lubricant in the passage 95 flows into a passage so as to lubricate the piston 49 of the compressor 15, as is described more in detail below. It will be seen that even when the unloader piston 86 is in its retracted position and the compressor 15 is unloaded that lubricant is supplied to the contacting moving surfaces of the piston and cylinder of the compressor through the sharp edged orifice 94. By a sharp edged orifice I mean an orifice having a length which is small compared with its diameter, having a comparatively abrupt entrance on the upstream side thereof, and providing for a predetermined flow of fluid therethrough substantially irrespective of the viscosity of the fluid flowing through the orifice. It is advantageous to use a sharp edged orifice to divert a portion of the lubricant from the unloader bore 84, since the amount of fluid passing through such an orifice is independent of the viscosity of the fluid. Thus the quantity of lubricant supplied through the orifice 94 to the compressor 15 will be independent of the viscosity of the lubricant which may, of course, vary widely due to the difference in temperature of the machine resulting from its operation under various conditions. The pressure of the lubricant supplied to the unloader 83 varies directly as the speed of the pump 64 and hence, as the speed of the motor 16, and the amount of lubricant which is diverted from the bore 84 through the orifice 94 varies directly as the square root of the pressure. Hence, the area of the orifice 94 is preferably so proportioned that it will divert all of the lubricant supplied to the unloader 83 until the motor 16 reaches a predetermined speed, about 60% full running speed. After the motor 16 reaches such predetermined speed the lubricant in excess of the amount which may be diverted through the orifice 94 is accumulated in the bore 84 and causes the piston 86 to move outwardly. The operating rod 88 is thereby caused to disengage the inlet valve 55a and the latter then being free to operate normally. As a consequence, the compressor 15 may at that time begin to compress gaseous refrigerant and the motor 16 will be loaded. Since the loading of the motor 16 is prevented until it reaches a predetermined speed, the danger of its drawing an excessive current at its starting is obviated. As was pointed out above, the quantity of lubricant flowing through the orifice 94 is not affected by viscosity so the motor 16 will always be loaded at the same speed regardless of the temperature and hence viscosity of the lubricant. The orifice 94 is so positioned in the sleeve 87 with respect to the passage 95 that it registers with the latter when the sleeve 87 is at the extremity of its travel to the right, as viewed in Fig. 2 and Fig. 6, and is also so positioned that when the sleeve 87 travels to the left the orifice 94 will not be covered by the wall of the cylinder 85 until the end of the passage 95 is uncovered by the end of the sleeve 87. Such uncovering of the end of the passage 95 by the sleeve 87 permits an increased quantity of lubricant to escape from the cylinder bore 84. The consequent reduction in pressure in the bore 84 limits the outward movement of

the piston 86 so that the orifice 94 is never covered by the cylinder wall 85 during the normal operation of the machine. Since the bore 84 of the unloader 83 is continuously in communication with the passage 95 irrespective of the position of the sleeve 87 and piston 86, lubricant may be continually supplied thereto at all times when the pump 64 is in operation.

The unloader 83 also serves to unload the compressor 15 after the electrical circuit of the motor 16 has been opened and the motor is coasting to a stop. If the compressor 16 were not unloaded during the coasting period the load imposed on the rotor 31 of the motor 16 by the compressor 15 would cause the rotor to stop suddenly when the power was cut off, jarring the machine. In the operation of the machine which I have illustrated, however, when the motor 16 slows down to a predetermined minimum speed, about 60% of full speed, either because the power thereto has been cut off, or for any other reason, the pump 64 will also slow down thus reducing the pressure of the lubricant supplied to the unloader 83. Since the pressure on the piston 86 is thus reduced, the biasing spring 90 will cause the operating rod 88 to engage the inlet valve 56 thus unloading the compressor 15.

It is particularly advantageous to locate the unloader 83 directly in the series lubricant circuit, so that the lubricant passes in series through the principal bearing 38 of the motor 16, the unloader 83 and about the piston of the compressor 15. When so arranged, the unloader 83 will thus unload the compressor if an insufficient quantity of lubricant is supplied to the bearing 38 and the piston 49 to insure the safe operation thereof. I have accomplished this result in the machine illustrated by providing the sharp edged orifice 94 in the sleeve 87, as described above, in order that the lubricant in the series lubricant circuit will pass continuously through the bore 84 of the unloader irrespective of the position of the unloader piston 86 and consequently the unloader 83 does not at any time stop the flow of lubricant in the series lubricant circuit. There is some danger that gaseous refrigerant may be trapped as in solution in the lubricant which is pumped to the contacting moving surfaces of the compressor 15 and the motor 16 especially in a closed compression system of the type illustrated. The lubricant and gaseous refrigerant are in direct contact in the casing 10, so that refrigerant gas may go into solution in the lubricant, and some of the lubricant may enter the compressor cylinder 51 and be circulated with the compressed refrigerant. If the lubricant is pumped to a closed unloader cylinder and only diverted therefrom when the unloader piston is in a position to load the compressor there would be danger of loading the compressor when the lubricant contained such a large quantity of refrigerant that insufficient lubrication of the bearings and the like would be had. In the arrangement which I provide, this danger is obviated since the bore 84 of the unloader is in constant communication with its outlet port 95 and any gaseous refrigerant which enters the bore 84 will be forced out into the passage 95 and can not accumulate in the bore 84 to move the unloader piston 86 to the unloading position.

Lubricant diverted from the unloader bore 84 through the outlet port 95 enters an annular groove 96 formed in the wall of the compression cylinder 51. A smaller cooperating annular groove 97 is formed in the piston 49. The groove

97 registers with the groove 96 when the piston 49 is in its extreme retracted position shown in Fig. 5. When in this position, lubricant flows into the groove 97 from the groove 96. At the same time, the refrigerant in the cylinder bore 50 is not under compression and hence there is little or no tendency for it to leak past the piston 49. As the piston 49 is moved to the left, the refrigerant in the cylinder bore 50 is compressed and at the same time the groove 97 moves out of register with the groove 96. The compressed gaseous refrigerant in the cylinder bore 50 tends to leak between the piston 49 and the surrounding wall of the cylinder 51. This leaking refrigerant enters the groove 97, however, and displaces a portion of the lubricant therefrom. This displaced lubricant is forced into the small clearance space between the piston 49 and the wall of the cylinder 51 and forms a seal, thus effectually preventing the escape of compressed refrigerant from the cylinder bore 50 without the necessity of providing packing rings or the like on the piston 49. When the piston 49 is again moved to its retracted position, the groove 97 comes into register with the groove 96 and since the lubricant is being rapidly circulated through the groove 96, any gaseous refrigerant which is entrapped in the groove 97 is carried away by a stream of lubricant and later returned to the main body of gaseous refrigerant as is explained below. This arrangement also effectually lubricates the contacting surfaces of the piston 49 and the cylinder 51.

Lubricant in the groove 96 is forced upwardly therefrom through an L-shaped conduit 98 which communicates with the upper side of the groove 96, the outer end 99 of the conduit 98 being closed. A small hole 100 is provided in the side of the conduit 98 and allows a portion of the lubricant in the conduit 98 to pass therefrom into a recess 101 formed in the top of the compressor 15. The recess 101 is covered by a plate 102 which is secured to the compressor by a screw 103. Lubricant passing through the recess 101 drains down across the valved end of the compressor 15 into a cup 104 which is secured to the side of the motor 16.

The main portion of the lubricant in the conduit 98 passes upwardly therethrough and is discharged therefrom through a vertically extending nozzle 105. The lubricant discharged from the nozzle 105 passes through an aperture 106 formed in a horizontal baffle 107 which is supported on studs 108 and 109, the studs being welded, or otherwise secured, to the top of the casing 10. An outwardly extending recess 110 is provided in the top of the casing 10 opposite the nozzle 105 and serves to distribute the lubricant discharged from the nozzle 105 evenly over the inner surface of the top of the casing 10. The lubricant thus distributed flows through notches 111 provided about the periphery of the horizontal baffle 107 and drains down the vertical side walls of the casing 10 to the reservoir formed in the bottom thereof. Since the exterior of the casing 10 is in contact with a body of cooling air, the lubricant passing over the inner surface of the casing 10 is cooled thereby. An annulus of fins 112 surrounds the casing 10 and aid in the dissipation of heat therefrom.

The lubricant which collects in the cup 104 flows therefrom through an aperture 113 into an annular chamber 114 formed between the top of the stator 33 and the end shield 35. The lubricant thus collected in the chamber 114 flows

downwardly through the slots 34a in which the energizing windings 34 are located and absorbs heat therefrom. After draining through the slots 34a in the stator 33, the lubricant is collected in a reservoir 115 provided in the lower end shield 36, where it surrounds the lower ends of the energizing windings 34. Lubricant supplied to the top of the crank 44 flows downwardly over the right hand side of the motor 16 into a cup 116, which communicates with the reservoir 115. The lubricant accumulated in the reservoir 115 flows therefrom through an aperture (not shown) provided adjacent one of the helical supporting springs 19. The lubricant directed on to the supporting spring 19 flows down the same and into the body of lubricant 62 in the reservoir formed in the lower section 12 of the casing 10.

The lubricating system and lubricant cooling system described above are not my invention, but are the invention of Christian Steenstrup and are described and claimed in his application Serial No. 1,319, filed January 11, 1935, and assigned to the General Electric Company, the assignee of my present invention.

In the operation of the refrigerating machine described above, gaseous refrigerant in the casing 10, which is at the low pressure existing in the evaporator 128, enters an intake muffler 117, passes through a conduit 118 to a chamber 119 formed in the muffle box 54 and is drawn therefrom through the valved intake passage 55 into the bore 50 of the compressor cylinder 51. Gaseous refrigerant compressed in the cylinder 51 by the piston 49 passes therefrom through the valved exhaust passages 56 into an exhaust chamber 120 formed in the muffle box 54 through a conduit 121 to an exhaust muffler 122 and from there through a conduit 123.

The conduit 123, which is relatively flexible, being made of copper tubing or the like, is secured to a relatively heavy rigid support in order to prevent vibration thereof. In the illustrative form of my invention, the conduit 123 is soldered, or otherwise secured, as indicated at 123a in Figs. 2 and 5, to the periphery of the motor 16, thus providing a rigid mounting for the conduit 123 which aids in suppressing noise due to the movement of the compressed gaseous refrigerant therein. A substantial portion of the conduit 123 is secured in this manner to the periphery of the motor 16, that is it extends about approximately one-sixth of the circumference of the motor. The conduit and muffler mounting described above is described and claimed in my copending divisional application Serial No. 26,797 filed June 15, 1935 and assigned to the General Electric Company, the assignee of my present invention.

The lower portion of the conduit 123 is helical in form, thus providing a resilient connection between the unitary compressor motor structure which is free to vibrate on the springs 19, 20 and 21 and the rigidly mounted casing 10. The increased length of the conduit 123 so provided also aids in dissipating the vibratory energy of the compressed gaseous refrigerant contained therein and hence in the suppression of noise caused thereby. The compressed gaseous refrigerant passes through a conduit 123 to a condenser 124 which is cooled by natural draft and which surrounds the casing 10 being mounted on the annulus of heat conducting fins 112. The compressed gaseous refrigerant is liquefied in the condenser 124 and flows therefrom through a conduit 125, a flow controlling float valve 126 and a conduit 127 to an evaporator 128. The evaporator

128 is supported in a cooling compartment on the heat insulated removable top 12a. The liquid refrigerant contained in the evaporator 128 is vaporized by the absorption of heat from articles contained in the cooling compartment in which the evaporator is located and the refrigerant thus vaporized passes from the evaporator 128 through a suction conduit 129 back to the casing 10. It will be noted that the discharge end 130 of the suction conduit 129 is located above the normal level of the lubricant 62 in the reservoir formed in the lower section 12 of the casing 10. The vaporized refrigerant thus discharged in the casing 10 is again drawn into the intake muffler 117 and the cycle, above described, is repeated. It will be seen that the casing 10 is normally filled with vaporized gaseous refrigerant above the level of the lubricant 62 and any refrigerant which may have been entrapped in the lubricant while the latter is passing through the compressor 15 and the motor 16 will be released from the relatively quiet body of lubricant 62 and will be again mingled with the low pressure gaseous refrigerant thereabove.

While I have shown a particular embodiment 25 of my invention in connection with a compression refrigerating machine, I do not desire my invention to be limited to the particular construction shown and described, and I intend in the appended claims to cover all modifications within 30 the spirit and scope of my invention.

What I claim as new and desire to secure by Letters Patent of the United States is:

1. A refrigerating machine comprising a refrigerant compressor, a plurality of parts having 35 contacting relatively moving surfaces, a lubricant reservoir, means including a closed series lubricant circuit for recirculating lubricant from said reservoir to said relatively moving surfaces to lubricate the same, means connected in said 40 series lubricant circuit for controlling the loading and unloading of said compressor, and means for causing said loading and unloading controlling means to unload said compressor in response to the supply of an inadequate supply of lubricant 45 to said relatively moving surfaces and including a sharp edged orifice for causing said loading and unloading controlling means to be unresponsive to changes in viscosity of said lubricant.

2. A refrigerating machine comprising a refrigerant compressor having a plurality of parts having 50 contacting relatively moving surfaces, means for supplying lubricant to said relatively moving surfaces, means including a chamber having an inlet and an outlet through which the lubricant 55 flows continuously to said moving surfaces and dependent upon a predetermined rate of flow of lubricant for loading said compressor when said lubricant is supplied to said relatively moving surfaces at a rate exceeding a predetermined value, 60 and means including a sharp edged orifice located at said outlet of said chamber for diverting a predetermined part of the lubricant from said chamber to said compressor irrespective of the viscosity 65 of the lubricant.

3. A refrigerating machine comprising a refrigerant compressor, means for supplying lubricant to lubricate said compressor, means including a chamber having an inlet and an outlet 70 through which the lubricant flows continuously to said compressor and dependent upon a predetermined rate of flow of lubricant for loading said compressor when said lubricant is supplied to said compressor at a rate exceeding a pre- 75

- terminated value and for unloading said compressor when said lubricant is supplied to said compressor and motor at a rate less than a predetermined value, and means including a sharp edged orifice located at said outlet of said chamber for diverting a predetermined part of the lubricant from said chamber to said compressor irrespective of the viscosity of the lubricant.

4. A refrigerating machine comprising a refrigerant compressor, means for supplying lubricant under pressure, means including a chamber accumulating said lubricant supplied under pressure for controlling the loading of said compressor, means including a sharp-edged orifice continuously diverting a predetermined part of the lubricant accumulated in said chamber irrespective of the viscosity of said lubricant for lubricating said compressor, and means diverting an additional part of the lubricant accumulated in said chamber when the pressure therein reaches a predetermined maximum.

5. A refrigerating machine comprising a refrigerant compressor, an unloader cylinder, a piston movable in said unloader cylinder, means supplying lubricant under pressure to said unloader cylinder for actuating said piston, means responsive to the movement of said piston for controlling the loading of said compressor, means including a constantly open port in said cylinder and a sharp-edged orifice registering with said port diverting a predetermined part of the lubricant from said cylinder irrespective of the viscosity of said lubricant for lubricating said compressor irrespective of the position of said piston in said unloader cylinder, and means diverting an additional part of the lubricant accumulated in said chamber when the pressure therein reaches a predetermined maximum for limiting the movement of said piston.

6. A refrigerating machine comprising a refrigerant compressor, a motor for driving said compressor, an unloader cylinder, a piston movable in said unloader cylinder, means including a pump driven by said motor and supplying lubricant under pressure to said unloader cylinder for actuating said piston, means responsive to the movement of said piston for controlling the loading of said compressor, means including a constantly open port in said unloader cylinder and a sharp-edged orifice registering with said port diverting a predetermined part of the lubricant from said cylinder irrespective of the viscosity of the lubricant for lubricating said compressor irrespective of the position of said piston in said unloader cylinder, and means diverting an additional part of the lubricant accumulated in said chamber through said port when the pressure therein reaches a predetermined maximum for limiting the movement of said piston.

7. A refrigerating machine comprising a refrigerant compressor, an unloader cylinder, a piston movable in said cylinder, means supplying lubricant under pressure to said unloader cylinder for actuating said piston, means responsive to the movement of said piston for controlling the loading of said compressor, means for biasing said piston toward a position in which said compressor is unloaded, means including a constantly open port in said unloader cylinder and a sharp-edged orifice registering with said port diverting a predetermined part of the lubricant from said cylinder irrespective of the viscosity of the lubricant for lubricating said compressor irrespective of the position of said piston in said unloader cylinder, and means diverting an additional part of the lubricant accumulated in said chamber through said port when the pressure therein reaches a predetermined maximum for limiting the movement of said piston.

8. A refrigerating machine comprising a refrigerant compressor, an unloader cylinder, a piston movable in said cylinder, means supplying lubricant under pressure to said unloader cylinder for actuating said piston, means including a valve and responsive to the movement of said piston for controlling the loading of said compressor, means for biasing said piston toward a position in which said compressor is unloaded, means including a constantly open port in said unloader cylinder and a sharp-edged orifice registering with said port diverting a predetermined part of the lubricant from said cylinder irrespective of the viscosity of the lubricant for lubricating said compressor irrespective of the position of said piston in said unloader cylinder, and means diverting an additional part of the lubricant accumulated in said chamber through said port when the pressure therein reaches a predetermined maximum for limiting the movement of said piston.

9. A refrigerating machine comprising a refrigerant compressor provided with inlet and exhaust valves, an unloader cylinder, a piston movable in said cylinder, means supplying lubricant under pressure to said cylinder for actuating said piston, means responsive to the movement of said piston and engaging one of said valves of said compressor for controlling the loading of said compressor, means including a constantly open port in said unloader cylinder and a sharp-edged orifice registering with said port diverting a predetermined part of the lubricant from said cylinder irrespective of the viscosity of the lubricant for lubricating said compressor irrespective of the position of said piston in said unloader cylinder, and means diverting an additional part of the lubricant accumulated in said chamber through said port when the pressure therein reaches a predetermined maximum for limiting the movement of said piston.

10. A refrigerating machine comprising a refrigerant compressor provided with inlet and exhaust valves, an unloader cylinder, a piston movable in said unloader cylinder, means supplying lubricant under pressure to said cylinder for actuating said piston, means responsive to the movement of said piston and engaging one of said valves of said compressor for controlling the loading of said compressor, means including a constantly open port in said unloader cylinder and a sharp-edged orifice registering with said port diverting a predetermined part of the lubricant from said cylinder irrespective of the viscosity of the lubricant for lubricating said compressor irrespective of the position of said piston in said unloader cylinder, and means diverting an additional part of the lubricant accumulated in said chamber through said port when the pressure therein reaches a predetermined maximum for limiting the movement of said piston.

11. A refrigerating machine comprising a refrigerant compressor provided with a compression cylinder, an inlet valve for said compression cylinder located at one end thereof, a motor for driving said compressor, an unloader cylinder carried by said compressor and arranged parallel to said compression cylinder and with one end

thereof adjacent said inlet valve, a piston movable in said unloader cylinder, means including a pump driven by said motor and supplying lubricant under pressure to said unloader cylinder for actuating said piston, means including a U-shaped operating rod secured to said piston and operatively associated with said inlet valve for controlling the loading of said compressor, means including a compression spring for biasing said operating rod toward a position in which it holds said inlet valve open, means including a constantly open port in said unloader cylinder and a sharp-edged orifice registering with said port diverting a predetermined part of the lubricant 10 from said unloader cylinder for lubricating said compressor, irrespective of the position of said piston in said cylinder, and means diverting an additional part of the lubricant accumulated in said chamber when the pressure 20 therein reaches a predetermined maximum for limiting the movement of said piston.

12. A refrigerating machine comprising a refrigerant compressor provided with a compression cylinder, an inlet valve for said compression cylinder located one end thereof, a motor for driving said compressor, an unloader cylinder carried by said compression cylinder and arranged parallel to said compression cylinder with one end thereof adjacent said inlet valve, a piston movable in said unloader cylinder, means including a pump driven by said motor and supplying lubricant under pressure to said unloader cylinder for actuating said piston, means including a U-shaped operating rod secured to said piston and operatively associated with said inlet valve for controlling the loading of said compressor, and means including a compression spring for biasing said operating rod toward a position in which it holds said inlet valve open.

13. A refrigerating machine comprising a refrigerant compressor, means supplying lubricant under pressure for lubricating said compressor, means for controlling the loading of said compressor in response to the pressure of said lubricant, and means including a sharp edged orifice for causing said loading controlling means to be unresponsive to changes in viscosity of said lubricant.

14. A refrigerating machine comprising a refrigerant compressor, means supplying lubricant under pressure for lubricating said compressor, means including a chamber accumulating said lubricant for controlling the loading and unloading of said compressor, means diverting part of the lubricant accumulated in said chamber for lubricating said compressor during loaded and unloaded operation thereof, and means including a sharp edged orifice for causing said loading and unloading controlling means to be unresponsive to changes in viscosity of said lubricant.

15. A refrigerating machine comprising a refrigerant compressor, an unloader cylinder, a piston movable in said cylinder, means supplying lubricant under pressure to said cylinder for actuating said piston, means responsive to the movement of said piston for controlling the loading of said compressor, and means including a sharp edged orifice diverting a predetermined part of the lubricant from said cylinder irrespective of the viscosity of the lubricant for lubricating said compressor when said compressor is unloaded.

16. A refrigerating machine comprising a refrigerant compressor provided with inlet and exhaust valves, an unloader cylinder, a piston

movable in said cylinder, means supplying lubricant under pressure to said unloader cylinder for actuating said piston, means responsive to the movement of said piston and operably associated with said inlet valve for controlling the loading of said compressor, and means including a sharp edged orifice in said piston and a constantly open port in said cylinder registering with said orifice when said compressor is unloaded for diverting a predetermined part of the lubricant from said cylinder irrespective of the viscosity of the lubricant for lubricating said compressor irrespective of the position of said piston in said cylinder.

17. A refrigerating machine comprising a refrigerant compressor provided with a compression cylinder, an inlet valve for said compression cylinder located at one end thereof, a motor for driving said compressor, an unloader cylinder carried by said compressor and arranged parallel to said compression cylinder, a piston movable in said unloader cylinder, means including a pump driven by said motor and supplying lubricant under pressure to said unloader cylinder for actuating said piston, means including a U-shaped operating rod secured to said piston and operatively associated with said inlet valve for controlling the loading of said compressor, means including a compression spring for biasing said operating rod toward a position in which it holds said inlet valve open, and means including a sharp edged orifice in said piston and a constantly open port registering with said orifice in said piston when said compressor is unloaded for diverting a predetermined part of the lubricant from said cylinder irrespective of the viscosity of the lubricant for lubricating said compressor irrespective of the position of said piston in said cylinder.

18. An unloading mechanism for a compressor or the like comprising a chamber having a movable wall, means supplying an accumulation of liquid under pressure to said chamber for actuating said movable wall, means responsive to the movement of said movable wall under the influence of said accumulation of liquid for controlling the loading of a compressor, and means including a sharp edged orifice having an unobstructed approach thereto for diverting a predetermined portion of said accumulation of liquid from said chamber irrespective of the viscosity of the liquid.

19. An unloading mechanism for a compressor or the like comprising an unloader cylinder, a piston movable in said unloader cylinder, means supplying an accumulation of fluid under pressure to said cylinder for actuating said piston, means responsive to the movement of said piston in said cylinder under the influence of said fluid for controlling the loading and unloading of a compressor, and means including a sharp edged orifice diverting a portion of said accumulation of fluid from said cylinder for causing said loading and unloading controlling means to be unresponsive to changes in the viscosity of said fluid.

20. An unloading mechanism for a compressor or the like comprising an unloader cylinder, a piston movable in said unloader cylinder, means supplying an accumulation of fluid under pressure to said cylinder for actuating said piston, means responsive to the movement of said piston for controlling the loading of a compressor, and means including a sharp edged orifice having an unobstructed approach thereto for diverting a predetermined portion of the accumulation of fluid

fluid from said unloader cylinder irrespective of the viscosity of the fluid.

21. An unloading mechanism for a compressor or the like comprising a cylinder provided with an outlet port in a side wall thereof, a piston movable in said cylinder and having a cylindrical portion extending beyond the head thereof and normally overlying said outlet port, means supplying an accumulation of fluid under pressure to said chamber for actuating said piston, means responsive to the movement of said piston for controlling the loading of a compressor, and means including a sharp edged orifice formed in said cylindrical portion of said piston and registering with said outlet port when said piston is in the unloading position for diverting a predetermined portion of the fluid accumulated in said cylinder irrespective of the viscosity of the fluid.

22. A refrigerating machine comprising a refrigerant compressor provided with a compression cylinder, an inlet valve for said compression cylinder located at one end thereof, a motor for driving said compressor, an unloader cylinder carried by said compressor and arranged parallel to said compression cylinder, a piston movable in said unloader cylinder and having a cylindrical portion extending beyond the head thereof, means including a pump driven by said motor supplying lubricant under pressure to said unloader cylinder for actuating said piston, means including a U-shaped operating rod secured to said piston and operatively associated with said inlet valve for controlling the loading of said compressor, means including a compression spring for biasing said operating rod toward a position in which it holds said inlet valve open, and means including a sharp edged orifice in the cylindrical portion of said piston and a constantly open port in said compression cylinder registering with said orifice when said piston is in the unloading position for diverting a predetermined part of the lubricant from said cylinder irrespective of the viscosity of the lubricant and for lubricating said compressor irrespective of the position of said piston in said cylinder.

23. A refrigerating machine including a closed compression system containing a vaporizable refrigerant and a lubricant in direct contact, a motor and a refrigerant compressor enclosed in said system, means supplying said lubricant for lubricating said compressor, means including said lubricant for controlling the loading of said compressor, and means dependent upon the presence of such an excess of said vaporizable refrigerant in said lubricant as to prevent adequate lubrication for causing said last mentioned means to unload said compressor and for maintaining said

compressor unloaded until said excess of vaporizable refrigerant is removed from said lubricant.

24. A refrigerating machine including a closed compression system containing a vaporizable refrigerant and a lubricant in direct contact, a motor and a refrigerant compressor enclosed in said system, means supplying said lubricant under pressure for lubricating said compressor, an unloader cylinder, a piston movable in said cylinder, means supplying lubricant under pressure to said cylinder for actuating said piston, means responsive to the movement of said piston for controlling the loading and unloading of said compressor, and means dependent upon the presence of such an excess of vaporizable refrigerant in said lubricant as to prevent adequate lubrication for causing said last mentioned means to unload said compressor and for maintaining said compressor unloaded until said excess of vaporizable refrigerant is removed from said lubricant.

25. A refrigerating machine including a closed compression system containing a vaporizable refrigerant and a lubricant in direct contact, a motor and a refrigerant compressor in said system, said compressor being provided with inlet and exhaust valves, means supplying lubricant under pressure for lubricating said compressor, an unloader cylinder, a piston movable in said cylinder, means supplying lubricant under pressure to said cylinder for actuating said piston, controlling means responsive to the movement of said piston and operatively associated with said inlet valve of said compressor for controlling the loading and unloading of said compressor, means including a compression spring for biasing said piston toward a position in which said compressor is unloaded, and means dependent upon the presence of such an excess of said vaporizable refrigerant in said lubricant as to prevent adequate lubrication for causing said controlling means to unload said compressor and for maintaining said compressor unloaded until said excess of vaporizable refrigerant is removed from said lubricant.

26. A refrigerating machine comprising a refrigerant compressor, means dependent upon the operation of said compressor for supplying a liquid under pressure, means for controlling the loading of said compressor in response to the pressure of said liquid, and means including a sharp edged orifice and an arrangement causing said liquid to flow through said orifice for causing said loading controlling means to be unresponsive to changes in viscosity of said liquid.

HARLEY H. BIXLER.
